O. D. CLOAKEY ET AL

CIGARETTE HOLDER

Filed Feb. 24, 1925

*Earl R. Tabell
Oral D. Cloakey*

INVENTORS

UNITED STATES PATENT OFFICE.

ORAL D. CLOAKEY AND EARL R. TAMBLIN, OF LOS ANGELES, CALIFORNIA.

DESIGN FOR A CIGARETTE HOLDER.

Application filed February 24, 1925. Serial No. 12,473. Term of patent 3½ years.

To all whom it may concern:

Be it known that we, ORAL D. CLOAKEY, a citizen of the United States, residing at 1532 N. St. Andrews Place, in the city of Los Angeles, county of Los Angeles, in the State of California, and EARL R. TAMBLIN, a citizen of the United States, residing at 814 South Hope Street, in the city of Los Angeles, county of Los Angeles, State of California, have invented a new, original, and ornamental Design for a Cigarette

Holder, of which the following is a specification, reference being had to the accompanying drawing, forming a part thereof.

The figure is a plan view of a cigarette holder showing our new design.

We claim—

The ornamental design for a cigarette holder as shown.

ORAL D. CLOAKEY.
EARL R. TAMBLIN.
